TOBACCO DISPENSER

Max Friedman, High Point, N. C.

Application December 30, 1947, Serial No. 794,685

8 Claims. (Cl. 206—41.1)

1

This invention relates to dispensing and more particularly to a device for containing and dispensing smoking tobacco or other fluent material, which may be used for supplying the same to a pipe, cigarette tube, or other device.

Combination containers and dispensers have been used heretofore but have been subject to criticism on account of the difficulty of properly feeding the loose material to the ejecting means, which this invention is designed to overcome. Other deficiencies found in prior devices include those of excess bulkiness and that of difficulty of operation.

It is an object of the present invention to provide a combined container and dispenser for fluent material which is of simple, inexpensive and durable construction, easy to operate, and adapted to efficiently dispense material with a minimum of effort.

A further object of the invention is to provide a combined container and dispenser for fluent material in which only a single continuous motion is necessary to feed the material into position to be ejected and to eject the same.

A further object of the invention is to provide a combined container and dispenser for fluent material which has means for automatically closing the same and retaining the parts in closed position against accidental opening in order that failure to close the device and careless handling will not result in loss of the contents.

A further object of the invention is to provide a combined container and dispenser for fluent material which may be easily carried on the person without causing unsightly bulges in the clothing.

Further objects and advantages of the invention will be apparent from the following description taken in conjunction with the accompanying drawings, wherein:

Fig. 1 is an elevation disclosing the use of the device for filling a pipe with tobacco;

Fig. 2, an elevation of the interior of the device of Fig. 1;

Fig. 3, a view similar to Fig. 2 with portions of the device in section;

Fig. 4, a section on the line 4—4 of Fig. 3;

Fig. 5, a view similar to Fig. 3 with the parts in another position;

Fig. 6, a section on the line 6—6 of Fig. 4;

Fig. 7, a perspective of the cam member;

Fig. 8, an end elevation of the device;

Fig. 9, an end elevation of the inner drum;

Fig. 10, a part sectional part elevational view of a modified form of the invention;

Fig. 11, a fragmentary view similar to Fig. 10 with the parts in another position;

Fig. 12, an end elevation of the device of Fig. 10 illustrating one application of its use;

Fig. 13, a section on the line 13—13 of Fig. 10;

Fig. 14, a view similar to Fig. 13 of another

2

modified form of the invention with the parts in a different position; and,

Fig. 15, a view similar to Fig. 14 of still another form of the invention.

Referring to the drawings and particularly to Figs. 1 to 9, the container dispenser comprises an outer drum 10 having a rear substantially circular wall 11 and an outwardly curved or concave rim portion 12 attached thereto by suitable means such as the crimping 13. The rim of the drum is provided with an outlet or dispensing aperture 17 and an elongated slot 27 for purposes to be described later. A door 14, hinged at 15 to the rim portion 12, provides the front wall of the container.

Within the container an inner drum 16 is provided which includes a rear wall 17 and an outwardly curved or convex rim portion 18. The rim portion 18 has cutout portions or slots 19 and 19' and connecting web portions 20 and 20'. A circular offset portion 21 is provided centrally of the rear face of the drum to house a coil spring 22. A guide member or pivot 23 is attached by suitable means to the rear face of the drum 10 and extends within the container, serving as a pivot about which the drum 16 may turn. A broadened extended portion of the member 23 has a transverse aperture 23' therethrough for the reception of a plunger or piston rod 24. The spring 22 has one end 28 attached to the member 23 and the other end 29 attached to the periphery of the housing 21 formed in the central portion of the rear face of the drum 16.

An actuator 25 is attached by suitable means to the inner drum 16 and has an arm portion 26 extending through the slot 27 of the rim 12 of the drum 10.

It is apparent that the drum 16 may be rotated about the member 23 by movement of the actuator 25, and that the coil spring 22 may store energy during movement of the drum in one direction in order to return it to its original position.

Attached to the rim 12 of the drum 10 within the drums is a cylinder 30 having a cylinder head 31 and a cap 32. A stud 33 may be threaded into the rim 12 of the container to secure the cylinder 30, the body 34 of the stud passing through the slot 19 of the drum 16. Within the cylinder 30 is an end of the rod 24 including a piston head 35 and shoulder 36 comprising a part of the rod 24. It is apparent therefore that the piston rod 24 is limited to reciprocatory movement within the cap 32 and guide member 23.

A cam member 38 comprised of facing member 55 39 and webs 40 and having a peripheral groove or aperture 41 is attached to the housing 21 by suitable fasteners 42. The aperture 41 is adapted to receive the rod 24 and reciprocatory movement of the rod may be produced by engagement of the edge portions defining the aperture 41 with the shoulder 43.

A tamper head 44 may be secured to the end of the rod farthest from the piston head to eject material from the container. Positioned within the cylinder 30 around a portion of rod 24 is a helical spring 45 which abuts the piston head 35 of the rod at one end and a cylinder cap 32 at the other.

An adapter 46 is attached or may be integral with the drum 10 at the outlet 47 corresponding to the extreme outward movement of the tamper head 44.

The inner drum 16 is so positioned relative to the outer drum 10 that at one extreme of movement as shown in Fig. 3, the adaptor aperture 47 will be closed by the web portion 20 of the drum, but rotation of the inner drum will place the cutout portion 19' of the drum over the outlet 47. Likewise, the cam member 38 is so positioned relative to the drum that the piston rod 24 may occupy its fully retracted position as shown in Fig. 3 when the outlet 47 is closed by the web portion 20, in order that rotary movement of the drum will move the piston rod 24 towards its position of ejection as shown in Fig. 5.

In the operation of the device shown in Figs. 1 to 9, loose tobacco may be placed within the drums when the door 14 of the outer drum is opened. After closing the door the tobacco will be securely retained therein unless the dispensing operation is carried out. In the dispensing operation the pipe or other device into which it is desired to deposit tobacco may be placed around the adapter 46 so that tobacco may be dispensed thereinto without spilling. Movement of the actuator 25 will produce rotary motion of the drum 16 within the container 10. Simultaneously, the cam member 38 will cause the piston rod 24 to move downwardly. After a short initial movement of the drum and rod, the outlet 47 will be in registration with the cutout portion 19' of drum 16 and tobacco will be forced through the opening by the tamper head 44 which is attached to the rod. The rotary movement of the drum 16 urges or feeds a portion of the tobacco into the space through which the tamper head moves, thereby assisting the dispensing operation. At the limit of the actuator's movement, it may be released, at which time the coil spring 22 will return the drum to its former position, and the helical spring 45 the rod to its former position. Successive movements of the actuator to dispense more tobacco may be made if desired.

Considering the modified forms of the device shown in Figs. 10 to 15, the device includes the outer drum 10 with rear wall 11 and door 14. In the device shown in Figs. 10 to 13 the inner drum 16 has a spring housing 21' and is constructed similarly to that of the previous form of the device; it is adapted to rotate on a member 23 of substantially the same construction. A piston rod 50 is provided having an offset central portion 51 and a tamper head 52. A guide member 53 is also provided and comprises a substantially circular member 54 having a flange 54' which is adapted to be positioned on the spring housing 21' and has a tubular arm 55 secured by a stud 56 to the periphery of the container 10. The guide member 53 also includes a slot 57 for the reception of a pin 58 attached to the rod 50, thus restraining the rod to reciprocating motion. The spring housing 21' includes a cam slot 59 for the reception of an extremity of the pin 58.

In the construction of the device it is con-

templated that the substantially flat circular member 54 will be positioned closely adjacent the flat surface of the housing 21' in order that the cam slot 59 will be covered and particles of tobacco from within the container not permitted to pass therethrough into the spring housing. Similarly, the offset portion 51 of the rod is constructed to closely overlie the slot 57 in order to prevent particles of tobacco lodging therein and interfering with the operation of the device.

In the operation of the device, movement of the actuator produces rotation of the drum 16 to permit tobacco to flow out through the dispensing aperture in the outer drum. Simultaneously engagement of the edges defining the cam slot 59 and that of the guide slot 57 with the pin 58 of the rod causes movement of the piston rod 50 from the position shown in Fig. 13 to that of ejection. After the actuator is moved to its extreme position it may be released at which point the coil spring 22 located within the housing 21' causes both the drum and the rod to return to their previous position.

The form of the device shown in Fig. 14 is similar to that in Fig. 13 except that the coil spring 2 and its housing 21' is eliminated, and a cylinder 60, attached by a stud 61 to the drum 10, is provided for the reception of an end of a piston 50' having a piston head 62 adapted to be engaged by a helical spring 63. A pin 58 is engaged by a cam slot 59' in the rear wall of the drum.

In the operation of this form of the device the energy for returning both the drum and the piston rod to its initial position is stored by means of the helical spring, instead of the coil spring of the previous form of the device.

The device shown in Fig. 15 includes both the coil spring 22 and the helical spring 63 of the two previous modifications, and the associated housings therefor. In this form of the device the drum and piston are returned to their initial positions by concurrent action of the coil and helical springs.

The invention contemplates the provision of a thin covering of leather, composition, or the like, for the container in order to render it substantially air tight and improve its appearance. It likewise contemplates the utilization of an inner drum of other types. For example, part or all of the rim portion 12 farthest from the rear wall 17 may be eliminated if desired and the web portion 20 may have a diagonal cutting edge for better cooperation with the internal surface of the rim 12 of the drum in dispensing and cutting off the flow of the tobacco.

Various forms of adaptors including those for pipes or cigarettes may be provided and the same may be integral with, permanently attached to, or removably attached to the container in order that various sizes and types may be employed as the user desires.

It is apparent that the invention comprises a simple, inexpensive, and durable container for tobacco or other fluent material which is adapted to dispense the same into a suitable receptacle by a single continuous movement or actuation which causes the material to feed into ejecting position and be expelled therefrom.

It will be obvious to those skilled in the art that various changes may be made in the invention without departing from the spirit and scope thereof and therefore the invention is not limited by that which is shown in the drawings.

and described in the specification but only as indicated in the appended claims.

What is claimed is:

1. A combination container and dispenser for fluent material comprising an outer drum having substantially circular front and rear walls and an outwardly curved rim with a slot and a dispensing aperture therein, said front wall comprising a door hinged to said rim to provide access to the interior of said drum, an adaptor associated with said dispensing aperture for cooperation with means for receiving the fluent material, a pivot attached centrally of the outer drum and extending inwardly thereof with a broadened portion having a transverse aperture therein, an inner drum rotatably mounted on said pivot within said outer drum having a substantially circular rear wall and an outwardly curved rim with cut-out portions extending a substantial distance around said rim and web portions intermediate said cut-out portions, an actuator attached to the rim of said inner drum and extending through the slot of the outer drum, an offset portion centrally of the inner drum providing with the rear wall of the outer drum a spring housing, a coil spring within said housing having one end attached to said pivot and the other to the inner drum whereby rotation of the inner drum in one direction will cause said coil spring to store energy for the return of said inner drum; a cylinder attached to said outer drum within said drums, a fastener extending through the cut-out portion of the rim of said inner drum and attaching said cylinder to said outer drum, a cap and a head for said cylinder, a rod having a piston head extending into said cylinder and through the aperture in said pivot, a spring surrounding said rod and abutting said cylinder cap and said piston head whereby movement of the rod in one direction will cause said spring to store energy for the return of said rod, a tamper element on said rod, a cam member attached to said inner drum for cooperation with said rod whereby movement of the actuator will produce rotation of said inner drum from a position where the web of said inner drum is in registration with the dispensing aperture of said outer drum to a plurality of positions where a cut-out portion of said inner drum is in registration with said dispensing aperture in order that material within the drums may be permitted to pass through the dispensing aperture and whereby rotation of said inner drum will cause said cam member to act on the shoulder of said rod and move the same and its associated tamper element toward the dispensing aperture to eject material therethrough from within the drums, and whereby rotation of said inner drum will feed material toward the space through which said tamper element moves.

2. A combination container and dispenser for fluent material comprising an outer drum having front and rear walls and a rim with a slot and a dispensing aperture therein, a door to provide access to the interior of said drum, a pivot attached to the outer drum with a portion having an aperture therein, an inner drum rotatably mounted on said pivot within said outer drum having a rear wall and a rim with cut-out portions extending a substantial distance around said rim and web portions intermediate said cut-out portions, an actuator attached to said inner drum through the outer drum, a portion of the

inner drum providing with the rear wall of the outer drum a spring housing within said drums, a spring within said housing having one end attached to said pivot and the other to the inner drum whereby rotation of the inner drum in one direction will cause said spring to store energy for the return of said inner drum; a cylinder attached to said outer drum within said drums, a fastener extending through the cut-out portion of the rim of said inner drum and attaching said cylinder to said outer drum, a cap and a head for said cylinder, a rod having a piston head extending into said cylinder and through the aperture in said pivot, a spring surrounding said rod and abutting said cylinder cap and said piston head whereby movement of the rod in one direction will cause said spring to store energy for the return of said rod, a tamper element on said rod, a cam member attached to said inner drum for cooperation with said rod whereby movement of the actuator will produce rotation of said inner drum from a position where the web of said inner drum is in registration with the dispensing aperture of said outer drum to a plurality of positions where a cut-out portion of said inner drum is in registration with said dispensing aperture in order that material within the drums may be permitted to pass through the dispensing aperture and whereby rotation of said inner drum will feed material toward the space through which said tamper element moves.

3. A combination container and dispenser for fluent material comprising an outer drum having front and rear walls and a rim with a slot and a dispensing aperture therein, a door to provide access to the interior of said drum, an inner drum rotatably mounted within said outer drum having a rear wall and a rim with cut-out portions and web portions intermediate said cut-out portions, an actuator mounted on said inner drum, a spring housing within said drums, a spring within said housing attached to said outer drum and to the inner drum whereby rotation of the inner drum in one direction will cause said spring to store energy for the return of said inner drum; a cylinder secured within said drums, a cap and a head for said cylinder, a rod having a piston head extending into said cylinder, a spring surrounding said rod and abutting said cylinder cap and said piston head whereby movement of the rod in one direction will cause said spring to store energy for the return of said rod, a tamper means on said rod, a cam member attached to one of said drums for cooperation with said rod whereby movement of the actuator will produce rotation of said inner drum from a position where the web of said inner drum is in registration with the dispensing aperture of said outer drum to a plurality of positions where a cut-out portion of said inner drum is in registration with said dispensing aperture in order that material within the drums may be permitted to pass through the dispensing aperture and whereby rotation of said inner drum will cause said cam member to act on said rod and move it toward the dispensing aperture to eject material therethrough from within the drums, and whereby rotation of said inner drum will feed material toward the space through which said tamper means moves.

4. A combination container and dispenser for

fluent material comprising an outer drum with a slot and a dispensing aperture therein, means to provide access to the interior of said drum, an inner drum rotatably mounted within said outer drum and having cut-out portions and web portions, means to cause rotation of said inner drum, energy storing means within said drums whereby rotation of the inner drum in one direction will cause said means to store energy for the return of said inner drum; a rod within said drums having tamping means associated therewith, means positioning said rod within said drums for axial movement, energy storing means associated with said rod whereby movement of the rod in one direction will cause said means to store energy for the return of said rod, means associated with one of said drums for urging said rod in one direction, and means whereby rotation of the inner drum will move said drum from a position where the web of said inner drum is in registration with the dispensing aperture of said outer drum to a plurality of positions where a cut-out portion of said inner drum is in registration with the dispensing aperture in order that material within the drums may be permitted to pass through the dispensing aperture, and means whereby rotation of said inner drum will cause said rod to move toward the dispensing aperture and whereby rotation of said inner drum will feed material toward the space through which said tamping means moves.

5. A combination container and dispenser for fluent material comprising an outer drum having front and rear walls and a rim with a slot and a dispensing aperture therein, a door to provide access to the interior of said drum, a pivot attached to the outer drum with a portion having an aperture therein, an inner drum rotatably mounted for pivotal movement about said pivot a rod positioned within said drums having an offset portion and tamping means, a pin attached to said rod, a guide member positioned within said drums having a slot therein for the reception of said pin, and a sleeve portion for the reception of a portion of said rod whereby said rod is guided for reciprocatory motion, a spring housing within said drums, a spring within said housing attached to said pivot and to the inner drum whereby rotation of the inner drum in one direction will cause said spring to store energy for the return of said inner drum; a slot in said spring housing providing a cam for cooperation with the pin attached to said rod whereby rotation of said spring housing will produce axial movement of said rod, and whereby rotation of said inner drum will move the same from a position where the web of said drum is in registration with the dispensing aperture of said outer drum to a plurality of positions where a cut-out portion of said inner drum is in registration with said dispensing aperture in order that material within the drums may be permitted to pass through the dispensing aperture, and whereby rotation of said inner drum will cause said cam member to act on the pin attached to said rod and move it and its associated tamping means toward the dispensing aperture to eject material therethrough from within the drums, and whereby rotation of said inner drum will feed material toward the space through which said tamping means moves.

6. A combination container and dispenser for fluent material comprising an outer drum with a slot and a dispensing aperture therein, means to provide access to the interior of said drum, 75

an inner drum having a web with cutout portions, a rod positioned within said drums, tamping means associated with said rod, a guide member positioned within said drums having means for guiding said rod, a spring housing within said drums, a spring within said housing attached to the inner and outer drums whereby rotation of the inner drum in one direction will cause said spring to store energy for the return of said inner drum; cooperating means between the spring housing and the rod whereby rotation of said spring housing will produce movement of said rod, and whereby rotation of said inner drum will move the same from a position where the web of said drum is in registration with the dispensing aperture of said outer drum to a plurality of positions where a cut-out portion of said inner drum is in registration with said dispensing aperture in order that material within the drums may be permitted to pass through the dispensing aperture, and whereby rotation of said inner drum will act on the said rod and move it and its associated tamping means toward the dispensing aperture to eject material therethrough from within the drums, and whereby rotation of said inner drum will feed material toward the space through which said tamping means moves.

7. In a combination container and dispenser for fluent material, an outer drum with a dispensing aperture and a drum rotatably mounted within said outer drum having a dispensing aperture normally out of registration with the aperture of said outer drum, said inner drum having a central portion with a cam slot, a cover plate overlying the central portion having a substantially straight slot and attached to said outer drum within said drums, and an ejector rod slidably attached to said outer drum within said drums, said rod having a member for reception in the slots in said central portion and said cover plate at their intersection whereby rotation of the inner drum will cause reciprocation of the intersection of the edges defining said slots thereby causing reciprocation of the rod, and whereby the dispensing apertures of said inner and outer drums may be moved into engagement for permitting the flow of material therethrough.

8. In a combination container and dispenser for fluent material, an outer drum and a drum rotatably mounted within said outer drum and having a central portion with a cam slot, a cover plate overlying the central portion having a substantially straight slot and attached to said outer drum within said drums, and an ejector rod slidably attached to said outer drum within said drums, said rod having a member for reception in the slots in said central portion and said cover plate at their intersection whereby rotation of the inner drum will cause reciprocation of the intersection of the edges defining said slots thereby causing reciprocation of the rod.

MAX FRIEDMAN.
